UNITED STATES PATENT OFFICE.

THORVALD HANSEN, OF EVERETT, MASSACHUSETTS, ASSIGNOR OF ONE-HALF TO A. HUN BERRY, OF WALTHAM, MASSACHUSETTS.

COP-CUTTING MACHINE.

SPECIFICATION forming part of Letters Patent No. 763,882, dated June 28, 1904.

Original application filed November 20, 1900, Serial No. 37,131. Divided and this application filed January 14, 1903. Serial No. 138,994. (No model.)

To all whom it may concern:

Be it known that I, THORVALD HANSEN, of Everett, in the county of Middlesex and State of Massachusetts, have invented a new and useful Improvement in Cop-Cutting Machines, of which the following is a specification.

In winding small cops—say cops wound upon a cop-tube one-half inch in length—I have found that better work is accomplished where a number of threads are wound upon a single long tube, each thread building up its own cop upon its own section of the cop-tube, and then the cop-tube is cut into lengths corresponding to the thickness of the cop.

In an application, Serial No. 37,131, filed by me November 20, 1900, I have shown a machine capable of winding a number of threads into a number of cops upon a single tube in the manner to which I refer, and in the same application I originally showed means for cutting such a cop-tube after it had been wound into a number of tubes, so that when, say, four cops were wound on one tube the tube should be cut between the cops into four short tubes, one for each cop. The present application is a division of the application referred to and shows the cutting mechanism therein first described.

My present invention, therefore, consists in means whereby a long cop-tube may be subdivided into a number of short tubes, and it will be understood by reference to the drawings, in which—

Figure 1 is a vertical section of the cutting mechanism, Fig. 2 being a cross-section of the cop and knife holder on line 2 2 of Fig. 1, showing one of the knife-blades in a cutting position and a cop-holder in position to hold the cop during the cutting operation.

It will be understood that this mechanism now to be described may be mounted upon one of the spindles of such a machine as is described in the above-named application, or it may be separately mounted and power applied to it, as may seem fit. I have shown it, however, as part of such a machine and have shown the cop-tube as wound with four threads

in the manner described in the said application.

A is a shaft made hollow at its end to form 50 a knife-holder B. Upon this shaft is a gear A', by means of which power may be applied to the shaft—as, for example, by engagement with the gear F' shown in my said application. Instead of this gear A', however, a pulley may 55 be substituted, if thought best.

A² is a housing which, with suitable bearings A³ for the shaft A, may be supported upon the table of the machine or in any other desired way.

The knife-holder B contains a spring b and a follower b' in front of the spring. The knife-holder B serves as a socket for the knife-sheath C, which sets into it and is held in place by a nut c, which engages with the threads 65 upon the exterior of the outer end of the knife-holder B.

The knife-sheath is hollow and contains a knife D pivoted therein. This knife has a projecting heel d, which is in position to be 70 engaged by the follower b', this heel d projecting above and rearward of the pivot d' of the knife. The upper side of the knife-sheath C is slotted lengthwise with a slot c' sufficiently wide to allow the knife to pass up 75 through it. The knife D, as shown, has three blades d², and its free end has an upwardly-projecting toe d³, by means of which the knife-blades d² are brought into use in the following manner: In the end of the knife-sheath 80 C is a diaphragm d⁴, through which passes a rod e, having an enlargement e', adapted to engage the under side of the toe d³. The rod e has about it a spiral spring e', and its further end is connected to a connection e', setting in the handle E, which is pivoted to a bracket F', attached to the side frame F, this construction being such that upon pushing in the handle E the knife is thrown up by the engagement of the portion e' with the toe d³, 90 so that the knife D is thrown up through the slot in the knife-sheath and its blades d² are forced into the inner surface of the cop-tube. This action also causes the follower b' to be

pushed back by the heel d of the knife against the force of the spring b . Upon the release of the handle E the spring b tends to throw down the knife into the position shown in Fig. 1, and the spring c^2 throws the handle back into its original position, also shown in Fig. 1. The spindle A is in rotation during this operation, and it is necessary that the cops G shall be held from turning in order that the knife-blades may encircle the interior of the cop-tube G' , and so separate the cop-tube into its proper number of parts. For this purpose there is shown in Fig. 2 a convenient form of grip for holding the cop, which grip consists merely of two jaws H of proper size and shape, which are hinged together at h , as shown in Fig. 2, so that the operator after putting the cop upon the knife-sheath and pushing it home against a suitable stop, such as D' , (which is merely a collar attached to the sheath by a set-screw D^2), applies the grip to the cop, holds the cop tightly, and pushes in the handle E . The knife-blades immediately enter the cop-tube and as they revolve with the sheath cut the cop-tube in the manner described into four lengths, one for each cop G , the knives being properly located for this purpose. The blade D may be removed to substitute another knife having a different number of knives thereon to correspond with the number of cuts needed.

What I claim as my invention is—

1. A cop-tube-cutting mechanism consisting in a rotary spindle adapted to receive a cop-tube, a bearing for said spindle, means whereby said spindle is rotated in said bearing, said spindle carrying within it a knife normally sheathed, and means whereby said knife is thrown into engagement with said cop-tube, as and for the purposes described.

2. A cop-tube-cutting mechanism consisting of a hollow rotary spindle adapted to receive a cop, a bearing therefor, means whereby said spindle is rotated in its bearing, said spindle carrying a spring and a follower, a pivoted knife, and means whereby said knife is thrown into engagement with said cop, said knife being provided with a heel projecting rearwardly beyond its pivot, adapted to engage said follower whereby said knife is normally held in a sheathed position, as and for the purposes set forth.

3. A cop-tube-cutting mechanism consisting of a rotary spindle, a bearing therefor, means whereby said spindle is rotated in said bearing, said rotary spindle carrying a knife concealed therein and adapted to receive a cop-tube about its periphery, said knife being normally out of engagement with said cop-tube, and means whereby said knife is thrown into engagement therewith, said means consisting of a rod adapted to engage with the free end of said knife and move it, as and for the purposes described.

4. A cop-tube-cutting mechanism consisting in a rotary spindle, means whereby it is rotated, said spindle being adapted to carry a cop-tube and carrying within it a pivoted knife normally sheathed, the free end of said knife being shaped as shown, in combination with a lever-handle carrying a plunger lying within said spindle and adapted to engage with the free end of said knife and means connected with said knife whereby when said knife is not engaged by said plunger it will be forced into a sheathed position, as and for the purposes set forth.

5. In a cop-tube-cutting mechanism, a rotary spindle adapted to receive a cop-tube, a bearing therefor, means whereby said spindle is rotated in said bearing, said spindle carrying within it a knife normally sheathed, and means whereby said knife is thrown into engagement with said cop-tube, in combination with means whereby said cop is held during the rotation of said spindle and said knife.

6. In a cop-tube-cutting mechanism, in combination, means for supporting a rotary horizontal spindle, a knife located within said spindle and provided with one or more blades, said spindle being slotted, means for forcing said blades through its slot and withdrawing said blades within said hollow spindle, said spindle being adapted to receive a cop-tube, and means whereby the cops upon said cop-tube may be held stationary during the rotation of the spindle, as and for the purposes described.

7. In a cop-tube-cutting machine, in combination a bearing, a hollow rotary spindle mounted and adapted to rotate in said bearing, said spindle being slotted longitudinally, a knife pivoted within said spindle and having one or more blades normally located within said spindle and adapted to be forced outwardly therefrom through said slot, means whereby said knife-blades may be so forced and may be retired, said spindle being adapted to receive a cop-tube carrying two or more cops, and means whereby said cops and said cop-tube may be held stationary during the rotation of said spindle, and said knives may be forced through said slot to cut said cop-tube, as described.

8. In a cop-tube-cutting machine, a bearing, a rotary hollow spindle mounted in said bearing and adapted to rotate therein, and means whereby it is rotated, a knife located within said spindle, said spindle being slotted in line with said knife, and said knife being provided with one or more blades located to be caused to project through said slot, means for normally retaining said knife-blades within said spindle, and means located within the free end of said spindle and disconnected therefrom, whereby said knife-blades may be forced through said slot in said spindle, as and for the purposes described.

9. The cop-tube-cutting machine above described, comprising a bearing, a rotary hollow spindle mounted in said bearing, a knife having one or more blades located in said spindle, said spindle being slotted, means for advancing and retracting said blades through the slot in said spindle, whereby a cop-tube carried by said spindle may be divided by said blades, as and for the purposes set forth.
10. The cop-tube-cutting mechanism above described, comprising a bearing, a rotary hollow spindle mounted in said bearing, a knife having one or more blades located in said spindle, said spindle being slotted, means for advancing and retracting said knife-blades through the slot in said spindle, and a stop on said spindle against which the edge of a cop-tube may rest, whereby said cop-tube may be divided into lengths by said blades between the cops wound thereon, as set forth.
11. In a cop-tube-cutting machine, a rotary spindle adapted to receive a cop-tube, a bearing therefor, means whereby said spindle is rotated in said bearing, said spindle carrying within it a knife pivoted at its rear end, means whereby said knife is normally sheathed in said spindle, and mechanism located at the front of said spindle whereby the front end of said knife is moved to bring the blades of said knife into engagement with said cop-tube without interfering with the rotation of said spindle.
12. In a cop-tube-cutting machine, a rotary spindle adapted to receive a cop-tube, a bearing therefor, means whereby said spindle is rotated in said bearing, said spindle carrying within it a knife pivoted at its rear end, means whereby said knife is normally sheathed in said spindle, and mechanism located at the front of said spindle whereby the front end of said knife is moved to bring the blades of said knife into engagement with said cop-tube, said means comprising a spring-controlled rod adapted to be moved longitudinally of said spindle, and a handle detachable from said rod and suitably mounted as described, whereby it may engage said rod and cause it to be moved longitudinally within the spindle, as and for the purposes set forth.
13. A cop-tube-cutting mechanism, comprising a cop-clamp adapted to hold a cop and tube, a knife, and means whereby the said knife and cop are moved relatively to each other so that the cop may be severed into two or more cop-tubes.
14. A cop-tube-cutting mechanism comprising a cop-clamp adapted to hold a cop and tube, a knife, means whereby the said knife and cop-tube may be revolved relatively to each other, and means to adjust the cop-tube and knife relatively to each other so that the cop-tube may be severed into two or more cop-tubes.
- In testimony whereof I hereunto set my name this 12th day of January, 1903.
- THORVALD HANSEN.
